UNITED STATES PATENT OFFICE.

HENRY P. KIRSH, OF WATERTOWN, SOUTH DAKOTA.

PORTABLE IRONING BOARD.

Application filed May 9, 1923. Serial No. 637,793.

My invention relates to a portable ironing board adapted to be attached to a table, shelf or wall bracket.

One object of the invention is to provide an ironing board of this character that has a comfortable height for ironing, and which may be easily detached and folded into a compact mass which will take up very little room and may be conveniently stored away in a closet.

Another object of the invention is to provide an auxiliary board detachably secured above the main board and adapted for use in ironing small articles and sleeves on garments. When not in use, this auxiliary board is detached from the main board to give more room when using the latter alone.

One advantage this ironing board possesses as compared with other ironing boards is that the board rests on top of the table instead of being flush with the bottom of the table top. This feature raises the board two or three inches above the ordinary ironing board so that, for instance, with a table thirty inches high, the top of the board will be thirty-one inches instead of twenty-nine inches or less which is entirely too low for comfortable use.

Another object of the invention is to provide a very simple construction for connecting the auxiliary board with the main board, and this is accomplished through the intermediary of the upper end of the supporting leg for the board and consists simply of a dowel pin on the under side of the auxiliary board slipping into a slot formed in the head portion of the leg.

In the accompanying drawing, one embodiment of the invention is illustrated; and—

Figure 1 is a side elevation and partial section of the ironing board erected against a table;

Figure 2 is a perspective view of the auxiliary board;

Figure 3 is a perspective view of the supporting leg; and

Figure 4 is a fragmentary bottom plan view of the main board.

This portable ironing board consists of three main parts, namely, the main board 10, a supporting leg 11, and an auxiliary board 12. The main board is long and narrow, preferably tapering at its free end and provided at its opposite end with a pair of cleats 13 rigidly secured to the under side

thereof. These cleats are spaced apart to conform to the width of a slot 14 running longitudinally in the main board 10 from the inner or supporting end thereof. The cleats project slightly beyond the edge 15 of the main board so as to form lower jaws 16 and the jaws are accordingly rabbeted as at 17 to a depth which approximately corresponds to the thickness of the table top to which the board is to be attached and to a length which exceeds the projecting portion of the jaws beyond the edge 15. In this manner, the top of the shelf or table 18 is adapted to slip in between the main board 10 and the top face of the jaws 16, as indicated in Figure 1, so that a firm grip is obtained by the main board on the table.

Midway between the two ends of the cleats 13 is a transverse journal 19 for the supporting leg 11. By mounting the leg 11 in this manner it is possible to place the leg either in the erected position, as indicated in full lines in Figure 1, or in folded position along the under side of the main board 10, as indicated by dot and dash lines in said figure.

The leg 11 has an enlarged head 20 at its upper end, which is intended to project beyond the top surface of the main board 10 when the ironing board is set up for use. This head has a flat top surface 21 extending parallel with the top surface of the main board 10 as indicated. The under side of the head 20 has a nose 22, which has also a flat surface extending parallel with the top surface 21. The forward edge 23 of the head extends perpendicular to the top surface 21 and the bottom surface 22, and has near its upper end, a narrow slot 24 which is also parallel to the top surface 21, and the purpose of which will be described later.

In the preferred form of the device the lower half of the leg 11 is split as at 25, thus furnishing a pair of straddled feet 26 held apart by means of a pin 27 at the lower end thereof. At the junction of these feet, a reinforcing rivet 28 is provided in order to prevent the splitting of the leg above this point. By spreading the feet 26, as indicated in Figure 3, a firmer support of the table is obtained against the floor upon which the leg is resting.

The auxiliary board 12 is substantially of the same contour as the main board 10 but much shorter and narrower than the latter. On the under side of the auxiliary board and

at its inner end, two parallel blocks 29 are secured running in the longitudinal direction of the board. The width of the space between these blocks is approximately the same as the thickness of the head 20 or the width of the slot 14 in the main board. Extending transversely through these blocks is a dowel pin 30 permanently secured in the blocks and adapted to engage in the slot 24 provided in the head 20, as best seen in Figure 1. The relative positions of the parts are such that a comparatively tight fit is obtained between the auxiliary board 12 and the head 20 with the dowel at the bottom of the slot 24. The under side of the auxiliary board rests on the flat top surface 21 of the head.

When the ironing board is stored away, the auxiliary table or board 12 is detached therefrom and the supporting leg 11 folded under the main board 10, as indicated in dot and dash lines.

To erect the ironing board, the feet 26 of the leg 11 are swung away from the main board sufficiently to permit its sliding over the edge of the table 18 or a shelf, so that the main board 10 rests on the top thereof, while the jaws 16 grip the under side of the table top 18. The connection between the main board and the table is sufficient to support the board freely, but in order not to strain the same too much, the supporting leg

11 is now swung so that the nose 22 of its head 20 rests on top of the table 18, while the feet 26 contact with the floor. This gives a very firm support to the main board not only in the vertical direction, but also in longitudinal and transverse directions of the board.

When the sleeve or auxiliary board 12 is needed, it is slipped over the head 20 along the top surface 21 thereof until the dowel pin 30 engages in the bottom of the slot 24, after which the outer end of the auxiliary board 12 is suspended freely over a portion of the main board, as seen in Figure 1.

Having thus described the invention, what is claimed as new is:

In a device of the character described, a support having a flat upper edge face and a vertical edge face, the upper end portion of said support being formed with a slot leading from its vertical edge face, a board removably resting upon the flat upper edge face of said support, depending cleats carried by said board in spaced relation transversely thereof for engaging opposite sides of said support, and a pin carried by said cleats and extending between the same for fitting into said slot when the board is mounted upon the upper end of said support.

In testimony whereof I affix my signature.

HENRY P. KIRSH. [L. S.]
